CLAIM

The ornamental design for the racket is, as shown and described.

DESCRIPTION

FIG.1 is a perspective view of a racket showing my new design;

FIG. 2 is a front elevation view hereof;

FIG. 3 is a back elevation view thereof;

FIG.4 is a left side elevation view thereof;

FIG.5 is a right side elevation view thereof;

FIG. 6 is a top plan view thereof; and,

FIG.7 is a bottom plan view thereof.

The broken lines illustrate portions of the racket that form no part of the claimed design.
